UNITED STATES PATENT OFFICE.

HIRAM A. KIMBALL, OF PHILADELPHIA, PENNSYLVANIA, ASSIGNOR TO
BENJAMIN C. EVERETT, OF SAME PLACE.

IMPROVEMENT IN TRUSSES.

Specification forming part of Letters Patent No. 170,273, dated November 23, 1875; application filed
November 5, 1875.

To all whom it may concern:

Be it known that I, HIRAM A. KIMBALL, of the city and county of Philadelphia, in the State of Pennsylvania, have invented a new and useful Improvement in Trusses, of which the following is a specification, reference being had to the accompanying drawings.

My invention, in the first place, consists in curving the spring crosswise, commencing to curve at the ends, where the spring is flattened, gradually increasing the curve to the middle of the length of the spring, whereby to gradually increase its stiffness thereto. In the second place, the invention consists in the combination of the pad-holder with one end of the spring, by means of a swivel connected with an adjustable slide, whereby the slide-holder is adjustable in two directions at right angles to each other. It is held in its adjusted position by means of set-screws, as hereinafter described.

In the accompanying drawings, Figure 1 is a top view of the spring A, having a pad-holder, C, in connection therewith. Fig. 2 is a front view of the same. Fig. 3 is a cross-section of the pad-holder C and spring A, at the line *xx* of Fig. 1. Fig. 4 is a cross-section of the spring A at the line *yy* of Fig. 1.

Like letters of reference in all the figures indicate the same parts.

A is the spring, which is curved laterally except a short distance at its ends, where it is flat. The curvature commences at these flat parts, very slightly and gradually increases to the middle of the springs, whereby to increase its stiffness in the middle.

In Fig. 4, which is taken at the point 2, the curvature, it will be seen, is much less than at the point 3, the middle of the spring. The curvature has gradually increased from the other end of the spring to its middle or point 3, in the same manner. At this point the spring has such a curvature, taken in connection with the thickness of metal, as is required

site to give it the proper stiffness, and as the curvature gradually decreases from the middle of the spring to its ends, sensitiveness in the pressure of these resilient parts is effected. Or, in other words, the leverage of the length of the spring is balanced by the change of curvature, and thereby sufficient strength is given to the spring by the curvature with a minimum weight of material.

B is a slide on one end of the spring A, to which the pad-holder C is attached. The slide is fastened in its adjusted position by means of the set-screw D. The lower end of the slide is slotted to receive the flattened part of the pin F, which is connected with the cheeks *aa* by means of the joint-pin *b*. The pad-holder C turns on the rounded part at *d* of the pin F, as a lateral adjustment is given it either to the right or left. It is held in its adjusted position by means of the set-screw H, which passes through the head or flange *f* of the pin F.

For increasing or decreasing the pressure of the pad, the holder C is adjusted by means of the set-screw I, the end of which bears upon the slide B, as seen in Fig. 3.

I claim as my invention—

1. The spring A, having a gradually-increased lateral curvature from its ends to the middle thereof, whereby to gradually increase the stiffness of the spring to that point, to balance the strength of the leverage of the spring by the change of curvature, substantially as set forth.

2. The combination of the pad-holder C, slide B, pins F and *b*, and set-screws H and I, for an inward, outward, and a lateral adjustment of the pad-holders, substantially as set forth.

HIRAM A. KIMBALL.
